UNITED STATES PATENT OFFICE

115,570

DESIGN FOR A KITCHEN SPOON OR SIMILAR ARTICLE

William Scrimgeour, Washington, D. C., assignor to William Scrimgeour, Engineer and Contractor, Washington, D. C., a partnership

Application January 5, 1939, Serial No. 82,176

Term of patent 14 years

To all whom it may concern:

Be it known that I, William Scrimgeour, a citizen of the United States, residing at Washington, District of Columbia, have invented a new, original, and ornamental Design for a Kitchen Spoon or Similar Article, of which the following is a specification, reference being had to the accompanying drawing, forming part thereof, and wherein:

Fig. 1 is a perspective view of a kitchen spoon or similar article showing my new design;

Figs. 2 and 3 are a plan view and side elevation, respectively, of the same; and

Figs. 4 and 5 are enlarged transverse sections through the same at lines 4—4 and 5—5, respectively, of Fig. 1.

The characteristic features of the design, in the kitchen spoon or similar article shown, consist in the elongated flat handle having a relatively narrow and thick inner section A, an intermediate section B of increasing width and decreasing thickness, and a relatively wide and thin outer section C, the side edges of the outer section being parallel.

I claim:

The ornamental design for a kitchen spoon or similar article, as shown and described.

WILLIAM SCRIMGEOUR.
